UNITED STATES PATENT OFFICE.

GEORGE E. HAIGHT, OF HARTFORD, CONN., ASSIGNOR, BY MESNE ASSIGNMENTS, OF ONE-HALF TO WILLIAM E. WINSOR, OF NEW YORK, N. Y.

CURRENT-CONTROLLING DEVICE FOR TORPEDO-BOATS.

SPECIFICATION forming part of Letters Patent No. 257,693, dated May 9, 1882.

Application filed June 14, 1881. (No model.)

To all whom it may concern:

Be it known that I, GEORGE E. HAIGHT, of the city of Hartford, in the county of Hartford and State of Connecticut, have invented 5 certain new and useful Improvements in Electrical Devices for Torpedoes; and I do hereby declare that the following is a full, clear, and exact description of the invention, which will enable others skilled in the art to which it appertains to make and use the same, reference being had to the accompanying drawings, which form a part of this specification.

My invention relates to a method of operating or controlling the propelling, steering, and 15 firing apparatus of a self-actuated torpedo-boat, which are carried therein by means of an electrical cable conneetion from the boat to a suitable operating-point, and proper electrical apparatus at each end of the cable or 20 wire for accomplishing the desired results.

For these purposes my invention consists of a transmitter or current-selector located in the boat and electrically connected with the different mechanisms for executing the functions 25 of the same, and also in connection with the operating key-board on shore, or other desirable directing-point, by a single wire, the whole being so constructed and arranged that each and every of the different functional mechanisms may be first brought into unison with the main line and battery through the transmitter or current-director by a comparatively 30 feeble current, which normally flows through the line, and then actuated by an increase of said battery-current.

It further consists of an electrically-connected clock mechanism located within a torpedo-boat, the escapement-wheel of which is adapted to be operated by a pawl carried by the armature 40 of an electro-magnet arranged within the main circuit, the opening or closing of the circuit at the operating or directing point causing, through said pawl and escapement, a revolving arm carried by an arbor of said clock mechanism to make and break connection with the wires leading to the several different functional mechanisms of the boat.

It further consists in a clock mechanism arranged at the operating or directing point, and 50 carrying a circuit making and breaking wheel, to the same arbor of which is attached a needle whose outer end is arranged to be arrested by

a series of stops attached to operating-buttons, the arrangement being such that when the needle rests against any one of the series of 55 stops—say “port”—the circuit is made or brought in unison with its corresponding port mechanism through a suitable transmitting apparatus in the boat.

It further consists of a locking device in 60 combination with the transmitter in the boat, whereby the clock mechanism may be locked at a stated number of revolutions—say two—of the revolving contact-arm when a slight current is flowing through the line, and adapted 65 to be unlocked by an increase of the battery-current, which overcomes the retractile spring of the armature of an electro-magnet not operative by the weaker normal current, the effect being to insure the unison of the revolving contact-arm with relation to the different functional mechanisms in the boat, and with their corresponding operating-buttons through the circuit-breaking wheel of the time mechanism at the operating or directing point. 75

It further consists in the employment of a battery-current sufficiently strong to throw into unison the several circuits leading to the several functional mechanisms of the boat through suitable apparatus at each end of the 80 main line, but not strong enough to actuate said mechanisms, the current passing out through a shorter circuit of less resistance; and, also, in the employment of a stronger current, which shuts out the shorter circuit, or 85 circuit of least resistance, and is of sufficient intensity to instantly actuate the mechanism of the boat desired, and in case of the fuse-circuit being made the fuse will be exploded by the contact of the boat with any obstacle; 90 and, finally, in the employment of a still stronger current adapted to be thrown in when the fuse or fire circuit is made, the effect of which will be to instantly fire the charge at the will of the operator. 95

It further consists in a series of operating buttons or keys, having projections designed to arrest the revolving needle of the clock mechanism at the desired points to open the different circuits through the transmitter in the boat, said buttons or projections being dependent upon each other for operation—that is to say, the pressing down of one button and its projection will cause any or every one pre-

viously pressed down to release itself, a releasing or unison button being also provided, which, when operated, releases all buttons held down and allows the needle to freely revolve a sufficient number of times to insure the unison of what I term the "key-board apparatus" and the transmitter in the boat.

It further consists in certain details of construction and arrangement hereinafter particularly described, and then set forth in the claims.

Figure 1 represents a top plan view of the key-board mechanism by means of which the torpedo-boat is directed in its movements, and 15 is arranged on shore or other suitable directing-point. Fig. 2 represents a similar view as Fig. 1, but showing the hinged top board or cover thrown back in order to illustrate its internal construction and arrangement. Fig. 3 20 represents a top plan view of transmitting apparatus arranged within the torpedo-boat. Fig. 4 represents a diagram view, designed to show in a single view the principle of the operation of my improved device, and illustrates the arrangement of the circuits and 25 means by which the increases of the battery-current are controlled. Figs. 5, 6, 7, and 8 illustrate details of escapement and escapement-wheel of time mechanism of the transmitter 30 and armature of electro-magnet for operating the same. Fig. 9 represents a side elevation of a switch apparatus for regulating the increase and decrease of the battery-currents, and Fig. 10 an end elevation of the same. Figs. 35 11 and 12 represent respectively a side elevation and partial section of the governing device of the time mechanism of the key-board and a top plan view of the same. Fig. 13 represents a detail elevation of one of the buttons or keys which arrest the motion of the indicator-needle of the key-board at different 40 points. Fig. 14 represents a detail view of the unison locking device of the current-selector.

Referring to the accompanying drawings, 45 A represents what I term the "key-board apparatus," and is placed at the operating or directing point on shore or other suitable position. This apparatus is located within and upon an inclosing-box. B represents a clock 50 mechanism or train of gears arranged within said box and driven by a suitable spring wound by the ratchet-lever C. It is also provided with a governor, D, (shown more particularly by Figs. 11 and 12,) which consists of two pivoted 55 oppositely-arranged frictional bearings arranged to rub against the inner wall of an inclosing-barrel through their centrifugal force, opposed to which are tension-springs connected to the bearings, so adjusted that the tension shall be overcome as the governor revolves rapidly.

Mounted upon a suitable arbor of the train of gears B is a circuit making and breaking wheel, E. This wheel is insulated from the 60 time mechanism A by an annular ring, F, of some insulating material. In the outer periphery of wheel E also are arranged inser-

tions G of insulating material, between which the conducting material H comes, thus presenting alternately a segment of conducting 70 material and a segment of non-conducting material of equal extent.

To the same arbor of the time mechanism B upon which is mounted wheel E is mounted a 75 wheel, I, keyed thereto, the outer end of which may be arrested at different points in the path of its revolution, for the purpose shortly to be described.

J J are metallic contact-springs arranged within the main-line circuit and upon the frame 80 of the time mechanism, but insulated therefrom. They bear against the circuit-breaking wheel E, and are so arranged with respect to each other and to the wheel E and its metallic and insulated segments that normally the springs 85 J J rest against the metallic portions, (which are continuous,) and the main-line current flows through the line. This normal or circuit-making position of the wheel E is secured by the relative arrangement of needle I and the series 90 of stops or keys for the same. In this instance I have provided the key-board with five different stops or keys, besides a unison-key. They are respectively designated "stop," "go," "port," "starboard," and "fire;" but I wish it understood that I do not confine myself to the exact 95 number of stops or keys, nor to their employment for the uses designated, as it is evident that I can increase or diminish the number of functions or substitute other functions 100 for those stated. Every one of these keys— "stop," "go," &c.—is so arranged within the circular path of the needle I that when said needle rests against any one of them the circuit opening and closing wheel E makes metallic contact with springs J J, and the circuit is made. The arrangement of the keys 105 "stop," "go," &c., is shown in Fig. 1 and in reverse in Fig. 2, and the position of the needle I when resting against them, respectively, is indicated by dotted lines in diagram view, Fig.

4. If the position of the needle is at stop-key and the go-key be pressed down, the stop-key will rise (by means of a device to be hereininafter described) and the needle will rotate by 115 the spring-driven train of gears until arrested by the go-key. The position of the needle will then lie along the dotted line marked "Go," Fig. 4. As the circuit-wheel E is keyed to the same arbor as the needle I, it is evident that the wheel E has accomplished the same degree 120 of revolution. This partial revolution has brought two of the insulated segments G against the contact-springs J J—one against each—and the circuit has been broken and 125 made again through said springs arranged within the circuit, the segment portions of the circuit-wheel E occupying the same relative position that they occupied when arrested by the stop-key. This breaking and making of the 130 circuit causes pulsations through the main line to the torpedo-boat, the utilization of which will be described further on. If the starboard-stop be pressed down, the go-stop will rise and

the needle rotate till stopped thereby, during which the wheel E will have opened and closed the circuit twice, for the reason that the needle and circuit-wheel revolved twice as far as they did when traveling from "stop" to "go," when they opened and closed the circuit once, from which it will be evident that if the needle rotates a full revolution it will, through wheel E, make and break the circuit five times, because 5 there are five keys, and correspondingly five conducting and five non-conducting segments of wheel E; and if it rotate three-fifths of a revolution—or, in other words, travel the distance of three stops or keys—it will make and 10 break the circuit three times, and if four-fifths, or the distance of four stops, it will open and close the circuit four times; but it will be obvious, as before indicated, that the number of 15 keys may be changed and the wheel E correspondingly modified.

Instead of employing two springs J J to break the circuit, only one might be used and the other end of the line connected with wheel E in such manner that the wheel E would still 20 be insulated.

The method of providing and controlling currents from the battery of different intensities is shown in Figs. 2, 4, 9, and 10.

K, Fig. 4, represents a galvanic battery, preferably composed of sixty elements or cells. From the fifth carbon or negative pole of the fifth element I connect a wire, a, leading to binding-post a' on the key-board apparatus. From thence wire a leads to the contact-point a², insulated from its supporting frame. Against this point a², and making metallic contact therewith, lies spring a³, whose inner end is secured to insulated post a⁴. A wire, a⁵, leads from spring a³ and connects with one of springs 35 J J, through both of which the current normally flows, from whence it passes off to the ground through wire a⁶. From the zinc or positive pole of element or cell No. 1 a wire, a⁷, passes to binding-post a⁸, from which the 40 main wire L leads to the transmitter and other mechanisms of the boat, and thence to earth, thus completing the circuit. If, when the circuit is thus made and the current of five elements is flowing through the line, it is desired 45 to increase the intensity or strength of the current, say, to thirty-five elements or cells, I connect the carbon or negative pole of the thirty-fifth element by a wire, b, leading to binding-post b'. From thence wire b² leads to contact-point b³, against which normally rests metallic spring b⁴. Point b³ and spring b⁴ rest upon an 50 insulated block. From metallic spring b⁴ a wire, b⁵, connects with the conducting metal frame b⁶ of switch apparatus M. Here the connection of the thirty-fifth element is broken. It cannot pass off through contact-point a², spring a³, nor ground-wire b⁷, because they are insulated. The current therefore flows through 55 contact-point b³ to spring switch-lever b⁸, arranged to be operated by button N. When, therefore, it is desired to throw in a current from thirty-five cells, as above stated, the but-

ton N is pressed down, which movement depresses switch-lever b⁹. Said lever then strikes spring a³, making metallic contact therewith, 70 and at the same time breaking the contact between point a² and spring a³, whereby the connection with wire a, leading to the fifth carbon, is broken. In the meantime the inner end of lever b⁹ has broken contact with post b⁸ and 75 makes metallic contact with point b¹⁰, which leads to earth through wire b⁷. The electric current then passes as follows: from thirty-five carbon to wire b, to binding-post b', to wire b², point b³, spring b⁴, wire b⁵, frame of 80 switch b⁶, through trunnion-posts and trunnion to switch-lever b⁹, where the current finds two routes—one through point b¹⁰ and wire b⁷ to ground, and the other through spring a³, wire a⁶, spring J, wheel E, spring J, and wire 85 a⁶ to earth. The current from the zinc or positive pole of the battery takes the usual course—that is, through wire a⁷, binding-post a⁸, line L, through the transmitter, to earth, or, more properly speaking, to the water. By this division the greater portion of the current is made to flow over the former route, as it presents the least resistance, thereby preventing the burning out of the contact-springs J located in the other route. Again, when it is 90 desired to have a still stronger current, or that of the entire battery, which is sixty cells, I connect the sixtieth carbon by a wire, c, which leads to binding-post c'. From thence wire c² connects with switch c³. This switch is normally held open by spring c⁴, and carries a projection, c⁵, adapted to make metallic contact with spring b⁴, and at the same time break contact with point b³. When the whole battery is used, the line-connections with the fifth 95 and thirty-fifth carbons are broken by pressing button N and operating lever c⁵, and the whole current takes the following route: from sixtieth carbon, through wire c, post c', wire c², switch c³, drawn around so as to make contact with spring b⁴, (the thirty-fifth carbon wire being broken through point b³), wire b⁵, frame b⁶, trunnion-posts, and trunnion, to lever b⁹, (which was previously held down,) where the current finds two routes, as before explained, 100 the current from the zinc pole finding a route through main line L to earth.

Having described my improved apparatus located at the operating or directing point, (with the exception of the special construction and arrangement of the go, stop, port, &c., keys or buttons, which will be described farther on,) I will now proceed to describe my improved transmitting device, whereby I am enabled to open up the several different circuits connecting the different functional mechanisms of the boat through a single line-wire.

O represents a time mechanism consisting of a train of gears driven by an impelling-spring or equivalent, the winding-post or arbor of which is P. This mechanism carries an escapement-wheel, Q, of novel construction, the outer rim of which carries a number of equidistant stops arranged to come in successive

contact with a vibrating pawl or escapement operated by the pulsations of the electric current through an electro-magnet and its armature. Mounted upon the same arbor that carries the escapement-wheel is an arm, R, rigidly secured thereto, the outer extremity of which is arranged to sweep a series of metallic plates in electrical connection with the different functional mechanisms of the boat. Intervening between these metallic plates are plates of insulating material. In this instance I have provided five metallic plates, d, e, f, g, and h, to correspond with the five keys "stop," "go," "port," "starboard," and "fire" on the key-board at the other end of the line or directing-point. From plate d a wire, d', leads to binding-post d², connecting with stop mechanism of the boat. From plates e, f, g, and h lead respectively wires e', f', g', and h' to binding-posts e², f², g², and h², connecting with the go, port, starboard, and fire mechanisms of the boat. When a less or greater number of functional mechanisms are desired the number of metallic plates in contact with arm R and number of stops on wheel Q are correspondingly modified, as also the number of keys on the key-board at the other end of the line.

The main line L is secured to binding-post L¹ of the transmitter. From said post L¹ a wire, L², leads to an electro-magnet, S, having a vibratory armature, S'. An adjustable limiting-stop, S², limits its outward movement due to the usual retractile spring. Upon the same shaft that armature S' is mounted is secured pawl or escapement T, vibrating in unison therewith. The arrangement and construction of the escapement and its actuating electro-magnet armature are shown in Figs. 3, 5, 6, 7, and 8. As there are five different circuits in the boat leading from plates d, e, f, g, and h, I arrange upon the escapement-wheel ten stops or teeth, or double the number of said plates, for a purpose shortly to be described. The alternate stops—viz., i i i i i—are arranged in one and the same plane, while the intervening stops, i' i' i' i', are arranged in one plane, but at the side or adjacent to the plane of the other series, thus making every alternate stop lie in a different but contiguous plane in relation to the next adjoining stops. The escapement or pawl T, operated by the vibration of armature S', carries at its outer extremity two lugs or detents, t t', projecting from pawl T, so as to lie within the circumferential path of the stops i i', the detent t abutting against stops i and detent t' against stops i'. There is sufficient intervening space between the two detents t t' to allow of the free passage of the stops of wheel Q whenever they are by the movement of the pawl released. Whenever the armature S' is attracted detent t rests against one of the stops i', and whenever said armature is demagnetized detent t rests against one of the stops i. Suppose, now, that the current is flowing through the line to which electro-magnet S is connected. Armature S' will be attracted and pawl T will engage stop i', as

shown by Fig. 3. If, now, the circuit be broken, armature S' will be withdrawn, detent t' will release stop i' and allow it to pass between the 70 detents by the downward movement of the pawl, and detent t will engage the next stop i, (see Fig. 6,) the vibratory movement of the pawl being sufficiently great to throw the detent t into the path of stops i at one limit of 75 its throw and detent t' into the path of stops i' at the other limit of its throw.

U represents another electro-magnet arranged within the main-line circuit. Its armature U' is held away from the magnet by a spring, j, of greater tension than the retractile spring of the armature S' of magnet S, so that the weaker normal current which flows through the main line will not affect armature U'. This armature, or a projection therefrom, 80 rests normally against post U², from whence a wire, k, leads to binding-post k', which in turn is connected with the earth. The main-line wire L², after entering electro-magnet U, is led to its armature U', where the current 85 ordinarily finds two routes, one through post U², wire k, post k' to earth, and the other through wire m (attached to the same armature) to binding-screw m', attached to the spring-driven train of gears O, which constitutes a conductor to post 90 r and its arm R, where it passes off through the various circuits of the functional mechanisms of the boat to the ground, according as said circuits are opened and closed.

V represents an arm loosely pivoted to the winding-arbor P of the train of gears, or to any other suitable point, the object of which is to insure of the transmitter being in unison with the key-board A at the directing-point. For this purpose the arm V is made of the 105 peculiar configuration shown by the drawings, so that at every two revolutions (from a given point, preferably the circuit of the stop mechanism) of the arm R of the transmitter, and (from the stop-key) of the needle I on the key-board, the arm R will become locked at said stop circuit plate d. This it will do by the abutment r of arm V coming in contact with pin l, secured to arbor r.

To provide for the unlocking of arm R a 115 lever, W, is used, one end of which is adapted to be operated by the armature U' of magnet U, which will cause the other end to trip the spring-pawl n, when the spring p will oscillate the arm V and carry the abutment r out of the path of pin l. This oscillating movement will be continued far enough to carry the notch v² of the series v' v² into the path of pin l when it rotates, through its first revolution, whereupon pin l will strike notch v², the effect 125 of which will be to oscillate the arm V sufficiently to throw pawl n into notch n'. Upon the second revolution of arm R and pin l the pin will strike notch v' and oscillate arm V still farther, or sufficiently to allow of pawl n entering notch n', when the abutment r will be again in the path of pin l, to arrest it at the completion of its second revolution.

The operation of my invention is as follows:

We will suppose the transmitter to be arranged within a torpedo-boat, the binding-post L' connected with the main line leading to the key-board A on shore or other directing-point, the 5 post k² leading to the earth, and the posts d² e² f² g² h² leading respectively to the stop, go, port, starboard, and fire mechanisms of the boat. The arm R, which is slotted longitudinally, so as to form a flexible contact-point 10 rests upon plate d. The needle I of the key-board A rests against the corresponding stop-key, and a current of five cells of the battery is flowing through the line. In other words, the current from the five cells passes from 15 fifth carbon, through wire a, post a', point a², spring a³, wire a⁴, springs J, wheel E, wire a⁵, to earth; and from zinc pole of first cell it passes by wire a⁶, post a⁷, line-wire L, post L', wire L², electro-magnet S, (whose armature it 20 attracts and holds the pawl T against one of the stops i' of wheel Q,) thence by same wire L² to electro-magnet U, thence to armature U', where the current finds two routes—one through wire m, post m', frame of train of gears O, ar- 25 bor r, arm R, plate d, wire d', post d'', through stop mechanism of the boat, to ground, the other through post U², wire k, post k', to ground. As the latter is the route of the least resistance, the current passes out through said route. 30 When, however, it is desired to operate the stop mechanism of the boat, the button or key N is pressed down, which cuts out the connection with the fifth carbon wire and throws in a current from thirty-five cells, as heretofore 35 fully described. This current, passing over main wire L, enters the transmitter at binding-post L', thence by wire L², through magnet S, into electro-magnet U, thence to its armature U'. This stronger current (or current from 40 thirty-five cells) is sufficient to attract said armature U' against its spring j, (not operative by the weaker current, or current from five cells,) whereby metallic contact of said armature with post U² and its ground-connection is 45 broken, and the current flows from said armature, through wire m, post m', frame of gearing O, arbor r, arm R, plate d, wire d', post d'', to the stop mechanism of the boat and ground, the current being of sufficient intensity to op- 50 erate said mechanism. This current of thirty-five cells, when attracting armature U', also actuates through said armature the lever W, causing it to trip pawl n of lever V and unlock the arm R and its gearing, as before set forth. When the button N is released the 55 normal current of five cells again flows through the line in the manner before stated. If, now, it is desired to start the torpedo-boat, the go-button is pressed down upon the key-board A, 60 which will release the needle at "stop," and it will rotate to said go-button and stop, during which partial revolution the wheel E, through its insulated segments, will break the circuit and then make it again. This operation will 65 have the effect, first, of demagnetizing electro-magnet S, when its armature will be withdrawn and pawl T will pass stop i' and en-

gage the next succeeding one, i, thus allowing arm R to make one-tenth of a revolution, or, in other words, to pass midway between plates d 70 and e upon the insulated material; and, secondly, upon the making of the circuit again armature S' will again be attracted, and pawl T will pass stop i' in contact therewith and take up the next succeeding stop i'', allowing arm R to 75 make another one-tenth revolution, bringing it upon plate e. The current will now flow from armature U' of magnet U through the two routes before stated, an increase of the battery-current cutting out the ground-circuit through 80 post U², and the current flowing through arm R, plate e, wire e', and post e'' to the go mechanism, its function will be executed. Should it now be desired to operate the starboard mechanism, the starboard-button on the key-board is pressed down, when the needle in rotating from "go" to "starboard" will cause the circuit-wheel E to make and break the circuit twice, whereby armature S' will be withdrawn and attracted twice, thus allowing arm 85 R to perform four-tenths of a revolution, when said arm will be on plate g, leading to the starboard mechanism of the boat. Its function is executed by an increase of the battery-current in the same manner as the stop and go mechanisms. The port mechanism is first brought in unison, and then executed in like manner. In like manner, also, the fire mechanism is brought in unison with the main wire and battery. When the current from thirty-five cells 90 flows through the fire mechanism it intensifies said mechanism only to that degree which would explode the fuse by the boat striking some obstacle which drives in a firing-pin and cuts out resistance-coils, as shown in patents 95 to J. L. Lay. This is what is termed "firing by contact." When, however, a current of sixty cells is thrown in, which is accomplished by holding down button N and drawing switch e' from label "Fire" to that of "At will," in the 100 manner heretofore stated, the fuse is instantly exploded by the strong current passing through the resistance coils.

The transmitting apparatus is preferably enclosed within a wooden box and placed in the 105 boat, so that it may be easily taken out and replaced.

The construction and arrangement of the stop, go, port, starboard, fire, and unison key X are shown by Figs. 1, 2, and 13. Z represents 110 a ring, provided with a spring, z, having its other end fixed to a stationary part, and it has a constant tendency to draw said ring in the direction of the arrow; Fig. 2, which ring is mounted loosely for that purpose. This oscillatory movement of ring Z is limited by pin z', extending within notch z² of the ring. Opposite the lower end, z¹, of each of the keys are notches z³ in the ring-plate. The projections z⁴ carry each an inclined face, z⁵, adapted to 120 engage the sides of the notches z³ and force ring Z in a direction opposite to that indicated by the arrow, Fig. 2. In Fig. 2, which is a 125 bottom view of the ring Z, the stop-button is

shown held down. The inclined face z^6 has forced, through its action against notch z^2 , the ring in a direction opposite that shown by the arrow until said incline has passed beyond the ring-plate, when ring-plate Z will, through the action of its spring z , rotate in the direction of the arrow, and the notch z^2 will pass over the catch made at the top of incline plane z^6 . If, now, the go-button were to be pressed down, its inclined face z^6 would move ring Z until notch z^2 would disengage itself from the catch of stop-button, which would instantly rise through the action of its spring z^6 . In the meantime the catch of the go-button at the top of the incline z^6 would have come into action and ring-plate Z , through its spring z , again rotated in the direction of the arrow, when the projection or pin z^4 would project into the circular path of the needle I and arrest it. In like manner the pressing down of any one stop results in the disengagement of any other one previously depressed or operated. The incline z^6 and catch of each button face in one direction, or that contrary to the direction indicated by the arrow, Fig. 2.

X represents a unison-button, and differs from the others only in that no catch at the top of incline z^6 is provided. This button therefore cannot be held down except when the finger is upon it. Its purpose is simply to release all buttons and allow the needle to make preferably two revolutions, which would result, through the revolution of circuit-wheel E , in bringing the arm R of the transmitting apparatus of the boat upon stop-plate d and in locking the train of gears through lever V , as before explained. This operation is secured by pressing down unison-key X and then letting go of it. Then, after needle I has performed one revolution, press down the stop-button, so that the needle will be arrested by it, when it has completed its second revolution. At the same time arm R of the transmitter has reached the corresponding stop-plate d the second time and has become locked. The unlocking of arm R has been heretofore described.

I am aware that unison-stops have been used which were operated by reverse currents or by other than electric mechanism; but I am not aware that a unison-stop has ever been actuated by a differentiation of force sent through the same wire, or that electric currents of differing force have been used to actuate different mechanisms in succession over the same wire by throwing more or less cells into the circuit.

My device is peculiarly adapted to use in torpedo-boats, as by my strong current I keep the escapement locked while actuating the unison-stop, and with the weak current I operate the escapement when the unison-stop is thrown out, thus securing the escapement against accidental displacement.

Having described my invention, what I claim, and desire to secure by Letters Patent of the United States, is—

1. A current-director located within a tor-

pedo-boat or other desirable point, consisting of a clock mechanism carrying a switch actuated by the armature of an electro-magnet 70 and having a switch-board electrically connected with the several different functional mechanisms of the boat, in combination with a key-board mechanism on shore or other suitable directing-point, electrically connected to 75 the current-director by a single wire, said mechanism consisting of a circuit making and breaking piece, with means, substantially as described, for operating the same.

2. The spring-driven switch, the series of 80 wires leading therefrom to the operative mechanisms of the boat, and the locking device, constructed substantially as described, and electrically connected with said switch to lock it at the unison-point, all constructed to act in 85 combination substantially as set forth.

3. The spring-driven switch consisting of a revolving switch-arm and its contacts with wires leading therefrom, as described, the locking device for holding said switch at the 90 unison-point, and the escapement or equivalent device, and connecting operating-wire, all in combination substantially as described.

4. The spring-driven switch, a locking device holding said switch at the unison-point, 95 which locking device is constructed so as to be controlled from a distant point by means of an electric circuit, substantially as described, an escapement device having several contact-points, wires leading from the switch 100 to several operative mechanisms, and a key-board and controlling-stops, substantially as described, whereby the escapement-wheel may be detained at any point by means of currents acting through a single wire, all in combination substantially as described.

5. A spring-driven switch having several operating-wires leading therefrom, as described, the locking device for the switch at the unison-point operated by an increase of 110 the battery-current, and the single escapement and pawl connected with said switch and controlled by the operator through an electromagnetic circuit, all in combination substantially as described. 115

6. The combination of the spring-driven switch, the unison-stop, and the several wires leading from the switch, with the escapement, 120 its pawl operated by an electro-magnetic circuit, as described, and the several keys and their connections, substantially as described, whereby the operator is enabled to throw the switch into line with any wire leading therefrom or to bring it to the unison-stop by means of a current operating through a single wire, 125 as set forth.

7. The combination, with a spring-driven switch, of two or more electro-magnets of different power, but connected to the same wire, whereby the switch may be controlled by throwing more or less electrical elements into the circuit through the single wire, substantially as described. 130

8. The combination of the spring-driven

switch, as R, and its connections, the unison-stop controlled by a current of a given power, the escapement and connections controlled by a current of different power, a single wire leading to both, and a battery constructed to throw greater or less currents through the wire, as set forth.

9. In combination with a notched oscillating ring, as described, a series of buttons or operating-keys having projections designed to arrest the revolving needle of a spring-driven or equivalent train of gears at the desired points, for the purpose described, said projections being so constructed and arranged that the pressing down of one button and its projection will cause any one previously pressed down to be released.

10. The combination, with a notched oscillating ring and a series of buttons or operating-keys, substantially as described, of a unison-key which, when operated, releases all buttons or keys held down and allows the needle to freely revolve, for the purpose substantially as set forth.

11. The herein-described method of propelling, steering, and firing a torpedo-boat from any suitable directing-point through an electrical wire connection, consisting, first, in the employment of a comparatively feeble normal current sufficient only to throw into electrical connection any one of the several operative

circuits, as described; secondly, in the employment of a stronger current of sufficient intensity to effect the desired movement of the boat through the circuit previously placed in electrical connection; thirdly, in transferring the current to the firing-circuit, whereby the torpedo will be fired by contact with an obstruction.

12. The herein-described method of propelling, steering, and firing a torpedo-boat from any suitable directing-point through an electrical wire connection, consisting, first, in the employment of a comparatively feeble normal current sufficient only to throw into electrical connection any one of the several operative circuits, as described; secondly, in the employment of a stronger current of sufficient intensity to effect the desired movement of the boat through the circuit previously placed in electrical connection; thirdly, in transferring the current to the firing-circuit; and, fourthly, in sending a still stronger current, whereby the torpedo will be instantaneously exploded.

In testimony that I claim the foregoing as my own I have hereto affixed my signature in presence of two witnesses.

GEORGE E. HAIGHT.
